during the operation of the machine, of operating mechanism having a variable period of operation dependent on the number of detachable members inserted into the machine, a hand lever, and a normally effective locking device for said operating mechanism rendered ineffective by the operation of the hand lever and retained in ineffective position by the inserted printing members during an operation of the machine.

11. In a machine of the class described, the combination with a plurality of detachable printing members insertible into the machine to print on record material, of an operating mechanism having a variable period of operation dependent on the number of detachable members inserted into the machine, a hand lever, and a normally effective locking device for said operating mechanism rendered ineffective by the hand lever in conjunction with the first inserted printing member, and retained in ineffective position by the inserted printing members during the operation of the machine.

12. In a machine of the class described, the combination with a plurality of detachable printing members insertible into the machine for printing on record material, of an operating mechanism capable of having a variable period of operation dependent upon the number of printing members inserted into the machine, a normally effective locking device for the operating mechanism retained in ineffective position by the inserted printing members at certain times during the operation of the machine, and means for retaining the locking device in ineffective position during the operation of the machine and at the times that this is not accomplished by the inserted printing members.

13. In a machine of the class described, the combination with a plurality of detachable printing members insertible into the machine for printing on record material, of an operating mechanism constructed to have a variable period of operation dependent upon the number of printing members inserted into the machine, a hand lever, a normally effective locking device for the operating mechanism rendered ineffective by the hand lever in conjunction with the first inserted destination device and retained in ineffective position by the inserted printing members at certain times during the operation of the machine, and means for retaining the locking device in ineffective position during the operation of the machine at the times that this is not accomplished by the inserted printing members.

14. In a machine of the class described, the combination with a chute, of a printing mechanism, detachable devices insertible into the chute for coöperating with the printing mechanism to effect the printing of

records on record material when the detachable devices are moved in the chute, operating mechanism capable of having a varying number of continuous cycles of operations dependent upon the number of said devices inserted into the machine and adapted to move one device in the chute from a certain position at each cycle of operation, and a lever operated by the operating mechanism to permit movement of one device from said certain position at a time and prevent movement of the other inserted devices which are to be moved later in the chute.

15. In a machine of the class described, the combination with a chute, of a printing mechanism, a plurality of detachable devices, a number of which may be inserted into said chute for coöperating with the printing mechanism to effect the printing of records on record material, means for moving one of the insertible devices at a time in the chute from a certain position, operating mechanism therefor, and means, operated by the operating mechanism, for permitting but one of the inserted devices moving in the chute at a time, and preventing movement of the other inserted devices which are to be moved later by said means.

16. In a machine of the class described, the combination with a chute, of a printing mechanism, a plurality of detachable devices, a number of which may be inserted into the chute, for coöperating with the printing mechanism to effect the printing of records on record material, means for singly moving said devices in the chute from a certain position, and means for holding one device at a time in this certain position and for preventing the succeeding device moving into such position until after said preceding device has been moved by said moving means.

17. In a machine of the class described, the combination with a chute, of a printing mechanism, a plurality of detachable devices insertible into the chute for coöperating with the printing mechanism to effect the printing of records on record material, means for moving one device at a time in the chute from a certain position, operating mechanism therefor, and a lever operated by the operating mechanism, one end of the lever being in position to retain one device in said certain position until said means is to move the device, the lever being operated so that this end is moved out of retaining position when said device is to be moved and so that the other end of the lever is moved at the same time in the path of the succeeding inserted device to prevent its movement.

18. In a machine of the class described, the combination with a main operating mechanism, of a printing means, a plurality of printing members for coöperating with

UNITED STATES PATENT OFFICE.

HORACE G. MARTIN, OF RUTHERFORD, NEW JERSEY.

KEY-HOLDER.

1,261,148.

Specification of Letters Patent. Patented Apr. 2, 1918.

Application filed June 29, 1916. Serial No. 106,650.

To all whom it may concern:

Be it known that I, HORACE G. MARTIN, a citizen of the United States, residing at Rutherford, in the county of Bergen, State 5 of New Jersey, have invented a new and useful Improvement in Key-Holders, of which the following is a specification.

My invention relates to an improved form of device for holding keys or similar objects.

Referring to the drawings, Figures 1, 2, 3 and 4 are illustrations of several types of my device which is preferably constructed of a single piece of wire bent in an appropriate manner. Fig. 1 illustrates a simple form of the device which will readily be understood. Beginning at the end *a*, the wire 1 leads to the left, then upward, to the right and downward, then around the 10 end *a* toward the observer and upward, forming a hook or bearing 2 for the end *a*, then to the right and downward, away from the observer and upward, extending the hook or bearing 2 for the end *b* of the wire 25 1, thence to the right, downward and to the left, terminating in the end *b*. To secure a key or similar object in the device, the end *a* or the end *b* of the device is lifted out of its hook or resting place and toward 30 the observer so that it can be slipped through an appropriate opening in the object to be secured, and is then replaced in the position shown in Fig. 1. The device is preferably made of wire or similar metal having a certain amount of resiliency, which is bent so 35 as to leave a certain amount of spring in the ends *a* and *b*, which normally holds them in their proper resting place shown in Fig. 1.

Fig. 2 illustrates substantially the same device as Fig. 1 but turned end about so as to show its other side, and having a metal plate 3 added thereto and bent or clamped about the upright portions of the wire 1. The course of the wire can be readily followed, beginning with the end *a*, thence to the right, upward, to the left, then downward, away from the observer and upward forming a hook or rest 2 for the end *a*, then 50 to the left, downward toward the observer and upward, extending hook or rest 2 for the end *b*, then to the left, downward and to the right, terminating at the end *b*. The metal plate 3 may be used to strengthen or 55 stiffen the mechanism, and also to enable

the owner to stamp thereon his initials, or it may carry some brief advertising data.

Fig. 3 illustrates a modification readily understood. The end *a* of the wire 1 rests in a hook or bearing made by a proper bending of the wire. The wire 1 leads from end *a* upward, to the right and downward, to the left, then curves around the end *a* toward the observer, downward in a semi-circular form and back behind the end *a* and to the right, forming a bearing or rest 2^a for the end *a*. The wire then curves about the end *b* of the wire 1, forming a hook or bearing 2^b for the end *b* similar to that formed for the end *a* except in the reverse 60 direction, then to the left, upward, to the right and downward, terminating in the end *b*. A metal clamp 3 may be bent around the adjoining upright portions of the wire, as 65 illustrated, so as to strengthen the device. 70

Fig. 4 illustrates another modification of my device. In this form the wire 1 is bent a little differently and the hook or rest for its ends is formed in an attachment instead of in a bend of the wire. The drawing 80 shows the end *a* of wire 1 in its normal position in a hook 3^a formed by bending the upper portion of a metal piece 3 in a circular form away from the observer and then downward, the lower edge of said hook 85 being shown in dotted lines. The metal plate 3 has two ears or projections 3^b, 3^c, which are bent or clamped around the upright portions of the wire 1, and it may also be provided with a hole 3^c for securing it to 90 a chain or other suitable means. The wire 1 is bent from the end *a* toward the left, then downward, to the right, and upward, where one of the metal clamps 3^b is secured, then to the right and downward where the other 95 clamp 3^b is secured, then to the right, upward and to the left, terminating in the end *b*. The end *b* in Fig. 4 is shown in the position which either end of the wire automatically assumes for placing objects on 100 the ring, when it is sprung out of its normal resting place. This last statement as to the ends *a* and *b* applies equally to all the several figures.

I claim:

1. A carrier for keys consisting of a piece of metal bent into a form substantially as illustrated and described and having its two ends sprung into a hook or holder portion while free to be sprung out of said holder 105 110

the combination with a plurality of insertible detachable controlling members, of a main operating mechanism capable of having a variable period of uninterrupted operation dependent as to extent on the number of detachable members inserted into the machine, manipulative means, and a normally effective locking device for said operating mechanism rendered ineffective by 5 said manipulative means and retained in ineffective position by the inserted detachable members during an operation of the main operating mechanism.

41. In a machine of the class described, 15 the combination with a series of insertible recording devices, of a receiver constructed to receive a plurality of said devices, a manipulative device, a variably operable driving mechanism, and a lock controlled jointly 20 by the manipulative device and the inserted devices for controlling the variable operations of the driving mechanism.

42. In a machine of the class described, 25 the combination with a series of insertible recording devices, of a receiver constructed to receive a plurality of said devices, a variably operable driving mechanism, and a positive stop for said driving mechanism controlled by devices inserted into the receiver. 30

43. In a machine of the class described,

the combination with a printing mechanism, of a plurality of printing members insertible into the machine for coöperating with the printing mechanism to print on record material, an oscillating arm and means for oscillating said arm, devices carried by and movable relative to said arm for engaging the printing device during movement of the arm in one direction whereby to feed the 40 members through the printing mechanism, and means for moving said devices relative to the arm.

44. In a machine of the class described, 45 the combination with a printing mechanism, of a plurality of printing members insertible into the machine for coöperating with the printing mechanism to print on record material, an oscillating arm and means for oscillating same, devices carried by and 50 movable relative to said arm for engaging the printing members during movement of the arm in one direction whereby to feed the members through the printing mechanism, and means automatically controlling movements of said devices.

In testimony whereof I affix my signature in the presence of two witnesses.

HAAKON A. MARTIN.
